CLAIM

The ornamental design for a micro hydraulic power generator blade, as shown and described.

DESCRIPTION

FIG. 1 is a perspective view of a micro hydraulic power generator blade showing my new design;
FIG. 2 is a front elevational view thereof;
FIG. 3 is a rear elevational view thereof;
FIG. 4 is a left side elevational view thereof;
FIG. 5 is a right side elevational view thereof; and,
FIG. 6 is a top plan view thereof.
